SLIDE VIEWER

Richard W. Lanigan, 1525 N. Patton Ave.,
Arlington Heights, Ill.

Filed Feb. 25, 1964, Ser. No. 78,775

Term of patent 14 years

(Cl. D61—1)

FIG. 1

FIG. 2

FIG-3

FIG-2

FIG-5

FIG-7

FIG. 1 is a perspective view showing the front, top and right side of a slide viewer embodying my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is an elevational view as seen looking along the optical axis of the viewer, and showing the slide receiving drawer thereof in the extended position;

FIG. 7 is a left-side perspective view thereof; and

FIG. 8 is a bottom plan view, on a reduced scale, of the viewer as shown in FIG. 1.

I claim:

The ornamental design for a slide viewer, substantially as shown.
